UNITED STATES PATENT OFFICE.

JOHN W. KIRSHMAN, OF CALIFORNIA, MISSOURI.

OIL-FEEDER.

SPECIFICATION forming part of Letters Patent No. 770,077, dated September 13, 1904.

Application filed March 8, 1904. Serial No. 197,194. (No model.)

To all whom it may concern:

Be it known that I, JOHN W. KIRSHMAN, a citizen of the United States, residing at California, Moniteau county, State of Missouri, have invented certain new and useful Improvements in Oil-Feeders, of which the following is a specification containing a full, clear, and exact description, reference being had to the accompanying drawings, forming a part hereof.

My invention relates to oil-feeders; and it consists of the novel features herein shown, described, and claimed.

In the drawings, Figure 1 is a view in elevation showing my improved oil-feeder in position for use on the cylinder of a Corliss engine. Fig. 2 is a horizontal section of the oil-feeder, on an enlarged scale, on the line 2 2 of Fig. 3 and looking downwardly. Fig. 3 is a vertical central section on the line 3 3 of Fig. 2 and looking in the direction indicated by the arrow. Fig. 4 is a cross-section on the line 4 4 of Fig. 3 and looking in the direction indicated by the arrow.

Referring to the drawings in detail, the Corliss-engine cylinder 5 has a steam-supply pipe 6, and the oil-feeder 7 is connected to the supply-pipe by the discharge-pipe 8. The pump-plunger casing 9 extends downwardly from the oil-receptacle 10, the bore 11 of the casing being horizontal and there being a passage 12 connecting the plunger-casing at a point intermediate of its ends to the oil-receptacle. The pump-plunger 13 is mounted in the bore 11, there being a stuffing-box 14 at the outer end of the plunger and there being a packing-ring 15 at the inner end of the plunger, so that oil in the receptacle 10 will pass through the opening 12 to the intermediate part of the plunger, so as to form an oil-packing around the plunger. An air-passage 16 leads through the inner end of the plunger, and said air-passage is controlled by the check-valve 17. A check-valve 18 controls the passage of air to the pump air-chamber 19. A lug 20 extends from the oil-receptacle 10, and an operating-arm 21 is connected to the pump-plunger 13 by the pin 22, operating in the slot 23, and the lower end of said arm 21 is connected

to the valve-shifting rod 24 by the sleeve 25, 50 mounted upon the shifting-rod and having the pin 26 sliding in the slot 27.

An adjustable check-valve 28 controls the passage 29, leading from the air-chamber 30, said valve being adjusted by the perforated 55 nut 31, regulating the pressure of the spring 32 upon the valve 28. The oil-receptacle 10 is provided with an air-tight filling-cap 33.

As the pump-plunger is operated by the reciprocation of the valve-shifting rod air is 60 forced into the oil-receptacle through the oil, so that the oil forms a trap to prevent the air from leaking backward through the pump. The air-pressure in the air-chamber will overcome the steam-pressure in the discharge-pipe, 65 and the air-pressure will force the oil through the discharge-pipe into the steam-pipe. The adjustable check-valve will prevent the accumulation of too much pressure on the oil.

I claim—

1. An oil-feeder comprising a suitable oil-receptacle having an oil-outlet; a pump-casing below the oil-receptacle; a pump-plunger in said casing and packed at both ends; the oil-receptacle communicating with the plunger at 75 a point between its ends, and there being an air-passage through the plunger to the oil-receptacle; and check-valves controlling said air-passage.

2. An oil-feeder comprising a suitable oil-receptacle having an oil-outlet; a pump-casing below the oil-receptacle; a pump-plunger in said casing and packed at both ends; the oil-receptacle communicating with the plunger at a point between its ends, and there being an 85 air-passage through the plunger to the oil-receptacle; check-valves controlling said air-passage; and an adjustable check-valve leading from the compressed-air chamber to limit the air-pressure.

3. An oil-feeder comprising a suitable oil-receptacle having an oil-outlet; a pump-casing below the oil-receptacle; a pump-plunger in said casing and packed at both ends; the oil-receptacle communicating with the plunger at 95 a point between its ends, and there being an air-passage through the plunger to the oil-receptacle; the discharge end of said air-passage

being submerged in the oil; and check-valves controlling said air-passages; substantially as specified.

4. In an oil-feeder; a suitable oil-receptacle having an oil-outlet; a pump-casing below the oil-receptacle in a horizontal position and formed integral with the casing of the oil-receptacle; a pump-plunger in said casing and packed at both ends; the oil-receptacle communicating with the plunger at a point between said packings; and there being an air-passage through the plunger to the oil-recep-

tacle; the discharge end of said air-passage being submerged in the oil; and check-valves controlling the air-passages; substantially as specified. 15

In testimony whereof I have signed my name to this specification in presence of two subscribing witnesses.

JOHN W. KIRSHMAN.
